UNITED STATES PATENT OFFICE

2,497,455

ARTICLE DISPENSING CONTAINER

Jerome A. Johnson, Chicago, Ill., assignor to
 Arvey Corporation, Chicago, Ill., a corporation
 of Illinois

Application May 13, 1947, Serial No. 747,616

3 Claims. (Cl. 220—20)

1

This invention relates to improvements in article dispensing containers, and is more particularly concerned with the provision of a container adapted to be filled with articles, such as pills, capsules, candy, etc., and having a pair of dispensing apertures normally disposed out of registry but adapted to be brought into registry to permit the removal of articles from the container.

This invention further contemplates the provision of an article dispensing container adapted to be inexpensively formed from a single blank of flexible material, such as cardboard, cut and scored to provide a plurality of hingedly connected outer wall sections and a movable inner wall section, the movable inner wall section and one of said outer wall sections being formed with article dispensing apertures.

This invention embodies other novel features, details of construction and arrangement of parts which are hereinafter set forth in the specification and claims, and illustrated in the accompanying drawing, wherein:

Fig. 1 is a top plan view showing an article dispensing container embodying features of this invention.

Fig. 2 is an end view of same.

Fig. 3 is a longitudinal sectional view taken along the line 3—3 of Fig. 1, showing the movable inner wall of the container in its closed position.

Fig. 4 is a longitudinal sectional view, corresponding to Fig. 3, showing the movable inner wall of the container in its open position.

Fig. 5 is a transverse sectional view taken along the line 5—5 of Fig. 1.

Fig. 6 is a plan view showing the blank from which the improved container is formed.

Referring now to the drawings for a better understanding of this invention, a single blank 7 is cut from a sheet of flexible material, such as cardboard, and scored on its outer face along the parallel longitudinally extending score lines 8, 9, 10 and 11, and along the parallel transverse score lines 12, 13, 14, 15, 16 and 17.

When the blank 7 is folded to form a container, the score lines 8 and 13 define a side wall 18 and a hingedly connected end flap 19. The score lines 8, 9 and 12 define a bottom wall 20 hingedly connected to the side wall 18. The score lines 9, 10 and 14 define a side wall 21, hingedly connected to the bottom wall 20, and an end flap 19' hingedly connected to the side wall 21. The score lines 10 and 11 define a top wall 22, hingedly connected to the side wall 21, and a side gluing flap hingedly connected to the outer

2

side of the top wall 22. Score lines 12 and 15 define a front end wall 24 hingedly connected to the front end of the bottom wall 20. Score lines 15 and 16 define an inner wall 25 hingedly connected to the front end wall 24. Score lines 16 and 17 define a rear end wall 26, hingedly connected to the inner wall 25, and an end gluing flap 27 hingedly connected to the rear end wall 26. Apertures 28 and 29 are formed in the top wall 22 and inner wall 25, respectively.

In folding the blank to form a container, the side walls 18 and 21 are first folded downwardly to positions disposed at right angles to the bottom wall 20, and the end flaps 19 and 19' are folded inwardly at right angles to their respective side walls 18 and 21. The front end wall 24 is then folded down against the outer sides of the end flaps 19 and 19', and the inner wall 25 is folded to a position in spaced parallel relation to the bottom 20. The top wall 22 is then folded inwardly, and the side gluing flap 23 is folded upwardly to engage and be adhesively united to the inner face of the side wall 18 by means of glue applied to either the inner face of the side wall 18 or the outer face of the gluing flap 23.

After a blank has been folded in the manner thus described to form a container, the articles of merchandise, such as pills, are inserted into the container through the unsealed rear end indicated at 31 in Fig. 3. After the container has been filled with merchandise, the rear end wall 26 is secured in closed position by means of the end gluing flap 27 adhesively engaged against the inner side of the bottom wall 20. It will be understood that staples may be employed in place of glue to secure the flaps 23 and/or 27 in assembled position.

After the container has been filled with merchandise with the rear end wall 26 secured in closed position, it will be noted, in Figs. 1 and 3, that the apertures 28 and 29 provided in the top wall 22 and inner wall 25, respectively are disposed in offset relation to normally prevent the passage of articles therethrough. To dispense articles from the container, the rear end wall 26 is pivoted inwardly, in the manner illustrated in Fig. 4, to move the inner wall in a forward direction and dispose its aperture 29 in alignment with the aperture 28 formed in the top wall 22. The container is then turned upside down to permit one or more articles to move by gravity through the opening provided by the apertures 28 and 29. If desired, a pull flap 32 may be provided on the front end wall 24, by perforating the end wall 55 along the line 33, to serve as a handle in moving

the inner wall 25 to its open or closed positions.

While this invention has been shown in but one form, it is obvious to those skilled in the art that it is not so limited but is susceptible of various changes and modifications without departing from the spirit and scope of the claimed invention.

I claim as my invention:

1. An article dispensing container comprising, a top wall, a bottom wall, side walls, end walls, said end walls being normally disposed in spaced parallel relation in a plane normal to said top and bottom walls and having their lower ends hingedly connected to said bottom wall, and an inner wall hingedly connected to the movable upper ends of said end walls for movement relative to said top wall, said top wall and inner wall having apertures normally disposed out of registry and adapted to be brought into registry by movement of said inner wall relative to said outer wall responsive to inward pressure exerted manually against one of said end walls.

2. An article dispensing container comprising, a top wall, a bottom wall, side walls, end walls, said end walls being normally disposed in spaced parallel relation in a plane normal to said top and bottom walls and having their lower ends hingedly connected to said bottom wall, an inner wall hingedly connected to the movable upper ends of said end walls for movement relative to said top wall, said top wall and inner wall having apertures normally disposed out of registry and adapted to be brought into registry by movement of said inner wall relative to said outer wall responsive to inward pressure exerted manually

against one of said end walls, and end flaps extending inwardly from said side walls to normally engage the inner side of one of said end walls.

3. An article dispensing container comprising, a top wall, a bottom wall, side walls, end walls, said end walls being normally disposed in spaced parallel relation in a plane normal to said top and bottom walls and having their lower ends hingedly connected to said bottom wall, and an inner wall hingedly connected to the movable upper ends of said end walls for movement relative to said top wall, said top wall and inner wall having apertures normally disposed out of registry and adapted to be brought into registry by movement of said inner wall relative to said outer wall responsive to inward pressure exerted manually against one of said end walls, end flaps extending inwardly from said side walls to normally engage the inner side of one of said end walls, said end flaps being hingedly connected to their respective side walls and having their upper edges disposed in spaced relation to said top wall to define a recess to receive said inner wall.

JEROME A. JOHNSON.
